C. C. Hines, ATTORNEY.

UNITED STATES PATENT OFFICE.

HENRY J. SMIDLEY, OF CHICAGO, ILLINOIS.

VACUUM CLEANER.

Application filed April 15, 1926. Serial No. 102,242.

This invention relates to vacuum cleaners and particularly to vacuum cleaners having combined therewith a brush mechanism or sweeping mechanism for promoting and increasing the efficiency of the cleaning action. More particularly the invention relates to cleaners in which a rotary vacuum producing fan or its equivalent and a brush mechanism are simultaneously driven from a common drive motor, such, for example, as an electric motor.

One object of my invention is to provide a cleaner in which the sweeper is driven from the drive motor by friction gearing having a normally positive driving action, but which is so constructed as to permit of a relative slip of the sweeper under a certain degree of resistance to its rotation, as when it engages a stubborn portion of a carpet, such slip allowing the sweeper to pass over such portion of the carpet without pulling off the nap or otherwise injuring the same.

Another object of the invention is to provide a construction and arrangement of the parts whereby the motor and fan may be mounted coaxially upon a common shaft extending in a single plane and preferably a suitably inclined plane adapting the device as a whole to be disposed at a convenient angle to the horizontal in order that it may be the more readily and conveniently manipulated by its operating handle and a more compact organization produced, such construction and arrangement of parts further permitting of greater simplicity of construction and enabling the use of sectional (double) drive shafts with universal joints, connecting gearing and other complex parts to be dispensed with.

Still another object of the invention is to provide a construction and organization of parts whereby greater efficiency of coaction between the sweeper mechanism and vacuum producing means may be obtained, and whereby free and unrestricted channels for the flow of air and collected dust are formed and the efficiency of operation thereby further increased.

Still another object of the invention is to provide a construction which adapts the device to have access to square or angular corners or other normally inaccessible portions of a room, thereby enabling all portions of a room to be cleaned with facility.

Still another object of the invention is to provide an angular formation of suction

head and arrangement of overlapping brushes whereby corners and other angles may be reached and effectually cleaned.

Still another object of the invention is to generally improve and simplify the construction, reduce the number of working parts, dispense with the use of parts requiring frequent repairs, and increase the efficiency and ease and facility of assemblage and disassemblage of the various elements of cleaners of the class to which my invention applies.

With these and other objects in view, the invention consists of the features of construction, combination and arrangement of parts, hereinafter fully described and claimed, reference being had to the accompanying drawings, in which:—

Figure 1 is a sectional plan view of the cleaner taken substantially on the plane indicated by the line 1—1 of Figure 2.

Figure 2 is a vertical longitudinal section of the same taken substantially on the plane indicated by the line 2—2 of Figure 1.

Referring now more particularly to the embodiment of my invention shown in Figures 1 and 2 of the drawings, 1 designates generally a casing enclosing the working parts. This casing includes a head portion or shell 2 consisting of side walls 3, a top wall 4, a rear wall 5 and short end walls 6 connecting the rear edges of the walls 3 with the side edges of the wall 5.

The walls 3 converge in a forward direction to a point and provide with the coacting walls a head or shell of substantially triangular form, said head or shell being open at the base, as indicated at 7. Arranged within the head or shell are shafts 8 and 9 on which are mounted rotary cleaning brushes 10 and 11, respectively, each consisting of a sleeve fixed to its shaft to revolve therewith and carrying rows of brush bristles. The shafts 8 and 9 are parallel with the sides 3 of the head or shell and extend forwardly in converging relationship toward the apex of the head. The shaft 8 is journaled in bearings 12 and 13 mounted on the wall 3 at one side of the head and the short rear end wall 6 at the opposite side of the head, while the shaft 9 is mounted in a rear bearing 14 on the other short rear end wall 6 and in a bearing bracket 15 extending inwardly from the adjacent wall 3 of the head. It will be observed that

the formation of the head is such as to

produce a substantially triangular-shaped vacuum and dust receiving chamber between the brushes 10 and 11 and the rear wall 5, and that the arrangement of the brushes is 5 such that one brush will sweep forwardly while the other brush will sweep rearwardly at the points of contact of said brushes with the carpet or floor. The wall 5 is preferably bowed or curved transversely and offset forwardly so as to lie in advance of the rear edges of the walls 6 and to a certain degree between the rear ends of the brushes, thus contracting the space or chamber 16 to a desirable degree and by this arrangement 10 also decreasing the overall length of the cleaner as a whole, this feature being one of several present in this structure for the production of a compact type of device. The brush 11 is shorter than the brush 10 and 15 terminates a distance substantially equal to the diameter of the brush 10 in rear of the apex of the triangular head, while the forward end of the brush 10 extends in advance of the forward end of the brush 11 20 and into the apex of the head. By this arrangement a reduction in width and length is obtained over any construction involving the use and arrangement of converging brushes of equal lengths, as will be readily 25 understood, and at the same time it will be seen that the forward end of the brush 10 overlaps the line of the brush 11 and sweeps in a direction across its path, giving the effect of two long brushes of equal length 30 arranged at oblique angles to each other. By the described formation of the head and arrangement of the brushes a cleaner is provided which will operate close to walls and other vertical surfaces and in corners or recesses of angular formation of a room, allowing 35 all portions of the floor of a room of any shape to be reached and cleaned with equal facility.

The brushes are so arranged that the 40 lower ends of the bristles project through the opening 7 so as to come in contact with a floor or carpeted surface and sweep the same in an efficient manner. The space or chamber 16 in which a partial vacuum is 45 formed and which initially receives the dust and other material collected, communicates through a discharge opening 17 with a fan chamber 18. This opening 17 and chamber 18 are formed respectively as a neck and 50 flanged out portion, respectively, of the wall 5, and such portions 17 and 18 lie substantially within the recess or alcove formed by the concaved side of the wall 5 between the 55 opposed end walls 6, thus further decreasing the length of the device and increasing its compactness. The chamber 18 is normally open at its rear and is covered by a rear motor chamber 19, the motor chamber 60 being closed at its rear end and having at its 65 forward end a flange 20 detachably secured

to the chamber 18 by screws or other suitable fastenings 21. In the chamber 18 is arranged a rotary fan 22 and in the chamber 19 is arranged a driving motor 23 of suitable type, an electric motor being shown in 70 the present instance. The fan 22 is driven by the motor 23 and when in action forms a partial vacuum in the hollow head or shell 2, whereby the vacuum cleaning effect is obtained, the dust and other materials drawn 75 by suction and swept up by the action of the brushes being collected in the chamber 16 and drawn rearwardly through the mouth 17 and between the blades of the fan 22 and discharging from the fan chamber through 80 a lateral discharge outlet 24. This outlet is suitably constructed to detachably receive a bag or other collector 25, which may be a bag of usual type and detachably secured to the outlet 24 in any preferred manner. 85

A drive shaft 26 extends longitudinally within the head 2, chamber 18 and chamber 19 and through the mouth or passage 17. This shaft is journaled at its forward end in a bearing 27 depending from the wall 4 of 90 the head 2, and is journaled at its rear end in a bearing 28 at the rear of the motor chamber 19. The shaft as a whole may be a one-piece shaft, formed by the armature shaft of the motor and a prolongation thereof, 95 or it may consist of two shaft sections, to wit, the armature shaft proper and a fan or brush driving shaft, formed separately but rigidly connected together. At its forward end this shaft carries a conical friction drive wheel 29 engaging friction wheels 30 of similar type mounted upon the forward portions of the brush sleeves or shafts, whereby the brushes are driven. The friction drive wheel 29 may be made of fibre, 100 rubber or other suitable material, and be provided with a concaved conical surface engaging the friction surfaces of the friction wheels 30 which may consist of solid tire-like bands of fibre, rubber or other similar material secured upon the wheel rims properly fixed to the brush shafts or other sleeves. By this construction the brush shafts will be positively driven at a corresponding and regulated rate of speed, but 110 the friction surfaces of the friction wheels permit of an independent slippage of either brush under a predetermined degree of resistance to the rotation of the brush. Thus, if the bristles of either brush encounter a 115 stubborn portion of a carpeted surface opposing a predetermined degree of resistance to its rotation, the brush may have a sufficient amount of slippage to adapt it to pass over such surface without rotation, or 120 at a slow rotation. By this means pulling out of the nap of the carpet or other injury thereto will be prevented. Any suitable means may, in practice, be provided 125 for adjustment of the friction wheels or oth- 130

er surfaces to regulate their frictional binding contact, no means of this kind being shown, as any ordinary means for the purpose may be employed, and as the same constitutes no part of my present invention. It will be observed that the casing comprising the parts 2, 18 and 19 extends, from the forward end of the portion 2, upwardly and rearwardly at an angle of inclination to the horizontal or to the floor surface. This angle of inclination is and preferably will be one of convenient character to dispose the rear of the device at a proper working elevation, without making it objectionably high. The angle of inclination is also such as to enable the operating handle, herein-after described, to be applied to the casing 19 at such an elevation that a forward push or a rearward pull may be exerted along a line coincident with the longitudinal axis of the cleaner, to enable manipulating power to be applied thereto to the best advantage, whereby the operator may grip the handle bar of the operating handle at a convenient elevation and manipulate the cleaner without a material degree of labor or fatigue. The shaft 16 extends within the casing at an angle of inclination corresponding thereto, and concentric with the axis of the casing, so that the fan 22 and motor 23 are directly, coupled and coaxially mounted. This construction adapts a unitary shaft to be employed for driving the brush mechanism, the fan and the motor, and does away with the use of two or more driving shafts arranged at different angles and connected by universal joints, gearing or other parts complicating the construction and which are liable to get out of order and require frequent repairs. Simplicity of construction is thus secured, with a reduction in the number of working parts, and with a saving in initial cost of construction to the manufacturer as well as costs for maintenance and repairs to the user.

For the purpose of holding the casing and its contained parts at a suitable elevation, and permitting the implement to be moved easily back and forth over a floor or other surface, a supporting bracket 31 is disposed at the rear and base of the chamber 18 and provided with a caster or roller 32. This bracket is suitably formed to hold the casing 18 at a desired elevation and may be slotted to receive a fastening and adjusting screw 33 detachably and adjustably securing it to the casing. At the vertex or nose portion of the shell 2 is positioned a contact piece 34 which is slotted for the passage of a securing and adjusting screw 35 detachably and adjustably securing it to the casing. This contact piece may be provided with a rounded, or other suitable contact surface, for engagement with the floor or carpet to hold the front portion of the cas-

ing at a desired working elevation. By adjusting the members 31 and 34 the degree of inclination of the casing with respect to the floor surface and level of the open sides 7 of the shell 2 with respect thereto may be varied and regulated within certain degrees. By this means the pressure of the brush bristles on the floor or carpet may be governed and the casing adjusted to compensate for wear of the brush bristles as may be required from time to time in the use of the device.

An operating handle 36 of any preferred type may be employed. As shown in the present instance, a handle of ordinary type in common use is disclosed, the same having a forked or yoked end embracing the chamber 19, the arms 36' of said fork being pivotally and detachably connected to said chamber by pivot screws 37. It will be observed that the construction of the head 2, chambers 18 and 19, and detachable connection of the two-last named parts permits of ready assemblage of all parts of the device and their disassemblage for cleaning, repairs and other purposes. As all parts also are of simple construction and durably connected and mounted the costs of manufacture and maintenance are reduced to the minimum.

From the foregoing description taken in connection with the drawings, the construction, mode of use and advantages of my improved combination vacuum and sweeper cleaner will be readily understood by those versed in the art without a further and extended description. While the constructions shown are preferred, it is to be understood that they are illustrated by way of examples, and that changes in the form, construction and arrangement of parts may be made, within the scope of the appended claims, without departing from the spirit or sacrificing any of the advantages of the invention.

Having thus fully described my invention, I claim:

1. In a cleaner, a suction head of substantially triangular form in plan and having its sides converging to an apex point at the front of the head, brushes arranged in V-formation in said head, and conforming in angular arrangement to said sides of the head, one brush being longer than the other and having its forward end extending in advance of the forward end of the other brush and lying in the angle between said sides at the apex of the head, and a shaft entering said head between and in driving connection with the brushes.

2. In a cleaner, a suction head of substantially triangular form in plan and provided with a vacuum chamber of substantially triangular form in horizontal section, forwardly converging brushes disposed in said cham-

ber, the rear wall of said chamber having a passage, a fan chamber communicating with said passage and provided with an outlet, a motor chamber at the rear of the fan chamber, said suction head and chambers being arranged at an upward and rearward angle of inclination to the horizontal and in axial alignment, a fan in the fan chamber, a motor in the motor chamber, and a shaft driven by the motor and connected to the fan and extending through said passage into the suction head and in driving connection with the brushes.

3. In a cleaner, a suction head, a pair of angularly related forwardly converging brushes disposed therein, one brush having its forward end terminating in rear of the forward end of the other brush, a gear element on the forward end of the first-named brush, a gear element on the second-named brush in rear of its end portion extending in advance of the first-named brush, a drive shaft in the angle between the brushes, and a gear element on said shaft engaging said gear elements on the brushes.

4. In a cleaner, a suction head having its side walls converging to an apex point at the front and having at its rear end wall portions relatively converging inwardly and rearwardly and arranged at right angles to said side walls, angularly related brushes in said head extending parallel with said side walls and forwardly in converging relationship, said brushes being journaled at their rear ends respectively in said end wall portions connected with the adjacent sides of the head, one of said brushes being shorter than the other and having its forward end journaled upon the head and terminating in rear of the apex of the head, the other and longer brush having its forward end extending across the head at the apex of the head in advance of the forward end of the shorter brush and journaled in the side wall of the head with which said shorter brush lies in parallel relation.

5. In a cleaner, a suction head of substantially triangular form in plan and having its sides converging to an apex point at the front of the head, brushes arranged in V-formation and each substantially parallel with one side of the head, one brush having

its forward end terminating in the rear of the forward end of the other brush and lying in the angle between said sides at the apex 55 of the head, gear elements on the forward ends of the brushes lying opposite each other, a drive shaft in the angle between the brushes, and a gear element on said shaft engaging said gear elements on the brushes. 60

6. In a cleaner, a suction head of substantially triangular form in plan and comprising side walls converging at their forward ends to an apex point, short end walls at the rear ends of said side walls and disposed at 65 right angles thereto, and a concavo-convex rear wall connecting said end walls and projecting forwardly a distance between the rear ends of the side walls, brushes in the head arranged in parallel relation to the 70 side walls and journaled at their rear ends in the end walls and at their forward ends upon one of the side walls, one brush being longer than the other and having its forward end extending in advance of the forward 75 end of the other and lying in the angle between the side walls at the apex of the head, gear elements upon the forward ends of the brushes lying opposite each other, a drive shaft arranged in the angle between the 80 brushes, and a gear element on said shaft engaging the gear elements on the brushes.

7. In a cleaner, a suction head open at its base, of substantially triangular configuration in plan, comprising side walls converging at their forward ends to form the apex 85 of the head and a concave rear wall extending across between the rear ends of the side walls and projecting a distance forwardly therebetween, a passage through said concave wall, a fan housing carried by said rear wall, and in communication with the interior 90 of the head through said passage, said housing lying substantially within the area between the said side walls, a fan within said 95 fan housing, a motor mounted rearwardly of said fan housing and connected with the fan to rotate the same, revolubly mounted brushes in said head, means connecting said motor with the brushes to rotate the same, 100 and a dust discharge outlet for said fan housing.

In testimony whereof I affix my signature.
HENRY J. SMIDLEY.
